ALKYLATION OF ISOPARAFFINIC HYDROCARBONS

William E. Bradley, Los Angeles, and Karl J. Korpi, Palos Verdes Estates, Calif., assignors to Union Oil Company of California, Los Angeles, Calif., a corporation of California

No Drawing. Application May 2, 1938,
Serial No. 205,532

2 Claims. (Cl. 196—10)

The present invention relates to the treatment of hydrocarbon oils, and refers to the manufacture of paraffinic hydrocarbons of a branched chain type particularly suitable for use in automobile and aviation engines. In a more specific sense, the invention comprises a process for the combining of isoparaffinic hydrocarbons of relatively low molecular weights with olefinic hydrocarbons to produce branched chain paraffinic hydrocarbons of higher molecular weight, boiling 10 within the gasoline range and particularly valuable as motor fuels or constituents thereof in view of their unusual anti-detonating characteristics. The invention further comprises the use of special catalysts and conditions of operation for the manufacture of these valuable compounds.

Since the present process is directed to the efficient utilization of certain olefinic and paraffinic hydrocarbons, particularly those found in commercial gas mixtures, and since the process produces hydrocarbons of high anti-knock value for use as motor fuels, the following discussion is given for the purpose of describing the character of these materials.

Olefinic hydrocarbons occur along with paraffinic and unsaturated hydrocarbons in various commercial hydrocarbon mixtures. For example, olefins are encountered in the products resulting from the cracking of petroleum, in gas making processes, and as by-products in various chemical industries. Also, they may be produced by the simple dehydrogenation of corresponding paraffinic hydrocarbons. In general, olefinic hydrocarbons are more chemically active than other classes of hydrocarbons. Thus, even under mild catalytic influences, olefinic hydrocarbons exhibit a high reactivity in their tendency to polymerize and form substances of higher molecular weight. On the other hand, paraffinic hydrocarbons, such as isobutane and isopentane, normally occurring in natural gas or similarly related materials, are usually considered to be more or less chemically inert and are incapable of polymerizing.

It is one of the objects of the invention to provide for a more effective utilization of certain of the isoparaffinic and olefinic hydrocarbons to produce valuable derivatives thereof. It is a further object of the invention to provide for a more effective utilization of the low boiling isoparaffinic hydrocarbons, namely isobutane, isopentane, and isohexane, and of certain olefinic hydrocarbons to produce branched chain hydrocarbons having high anti-detonating characteristics and boiling substantially within the gasoline range. The process described herein may also be applied to

individual olefins and isoparaffins as well as to their mixtures.

The reaction between one or more isoparaffinic molecules and one or more olefinic molecules produces an alkylated paraffinic molecule of a branched chain type. This product is herein referred to as "alkymer" in order to distinguish it from a "polymer" which is the product resulting from the interaction of two or more olefinic molecules. Theoretically, the reaction between an isoparaffin and an olefin in the presence of a suitable alkylating catalyst is of a simple character. Thus, the combination which takes place when isobutane is chemically combined with a butene may be expressed as follows:

The above equation shows the union of one 20 molecule of isobutane to one molecule of butene to produce one molecule of iso-octane. Similar reaction equations may be written for the alkylation of the above or other isoparaffins with various olefins.

As will be brought out more fully hereinbelow, 25 the term "alkylation" as employed herein includes not only the simple chemical combination of isoparaffin molecules with the olefinic molecules introduced into the sphere of reaction, but also the union between the specified isoparaffinic and olefinic molecules formed in situ as by the splitting of relatively larger molecules.

Olefins, when subjected to proper reaction 30 temperatures and pressures in the presence of a suitable catalyst, such as sulfuric acid, tend to form polymers. In fact, this tendency to polymerize, at least under certain conditions, occurs in preference to alkylation so that if a mixture of isoparaffinic or even cyclic hydrocarbons and olefins 35 is brought into contact with sulfuric acid, the reaction products will be found to contain only a relatively small percentage of alkylated products of reaction, the greater proportion of the olefins and particularly the more reactive olefins having 40 polymerized to produce unsaturated polymers in preference to their addition to the isoparaffinic or cyclic hydrocarbons.

The above described alkylation reactions may 45 be realized by reacting the isoparaffinic and olefinic hydrocarbons in the presence of suitable alkylating catalysts such as sulphuric acid, and particularly strong sulphuric acid. However, this strong acid tends to react to a certain degree with the hydrocarbons treated, this side reaction causing 50 the formation of by-products which progres-

sively decrease and may finally completely inhibit the catalytic activity of the acid.

It is therefore the main object of the present invention to provide a process wherein alkylation of the isoparaffins with the olefinic hydrocarbons shall be favored in preference to the polymerization of the olefins introduced into the reaction zone for the purpose of combining with the isoparaffinic hydrocarbons. It is a further object of the invention to provide a process wherein valuable motor fuel fractions having high anti-detonating characteristics may be produced by efficient alkylation of low boiling isoparaffinic hydrocarbons with normally gaseous and liquid olefins above ethylene and preferably having not more than about 12 carbon atoms in the molecule. It is a still further object to provide a process of the type described wherein the alkylation reaction is favored and wherein substantially no polymerization of the olefins occurs.

It has now been found that the above and other objects may be attained by adding certain oxidation inhibiting or mitigating agents to the alkylation catalyst. It has further been discovered that the oxidation inhibiting or reaction mitigating agent to be employed in connection with the alkylation catalyst may be selected from the polyhydric alcohols, such as glycols or glycerine, mixed polyhydric alcohol ethers, for example the mono-, di- or tri-butyl ethers of ethylene or di-ethylene glycols, as well as from the higher boiling aliphatic ethers such as diethyl ether, or mixtures thereof. These substances, or their mixtures, may be employed in connection with various alkylation catalysts such as sulphuric acid, benzene sulphonic acid, phenol sulphonic, etc. Particularly, the described agents find utility when employed with the stronger acid catalysts, such as strong sulphuric acid, which possess the above described oxidizing tendencies.

Various proportions of the oxidation inhibiting or reaction mitigating agents may be employed. However, relatively small proportions, for example proportions ranging from about 1% to 10% of the total catalyst employed, are adequate to reduce and even eliminate the tendency toward undesirable reactions. These relatively small quantities of the above agents furthermore increase the alkylation activity of the catalyst in that the products of reaction contain greater quantities of alkymers boiling within the gasoline range as compared to the yields produced by the use of the given catalyst alone. Also the life of the alkylation catalyst of the above described type is prolonged by the addition thereto of the described oxidation inhibiting or mitigating agents.

The term "isoparaffins" and "isoparaffinic hydrocarbons" as employed in the specification and claims, relate to the lower isoparaffinic members, namely isobutane, isopentane and isohexane. It has been found that the rates of alkylation of those isoparaffinic hydrocarbons, maintaining other conditions equal, are not the same. Thus, the rate of alkymer formation when isopentane is employed is considerably slower than the rate of alkylation of isobutane, while the alkylation rate of isohexane is even still lower.

As to the terms "olefins" and "olefinic hydrocarbons," they relate both to the normally gaseous olefins which comprise the hydrocarbons between about propylene and pentenes, and to the normally liquid olefins such as the hexanes and the higher olefins. It is to be noted, however, that it is not desirable to employ very high

boiling olefins since the alkylation reaction becomes unfavorable when such very high boiling olefins are employed. Thus, it is preferable, although not absolutely essential, to use fractions having olefins of not more than 12 carbon atoms per molecule.

It is to be further understood that the reference to isoparaffinic and olefinic hydrocarbons includes the use of these hydrocarbons individually, in mixtures with other hydrocarbons of the particular class or mixtures thereof with other hydrocarbons.

In one of its broadest concepts, the invention may therefore be stated to reside in reacting isoparaffinic hydrocarbons of the type of isobutane, isopentane and isohexane, with normally gaseous or normally liquid olefinic hydrocarbons, or with both types of olefins, in the presence of an alkylation catalyst containing oxidation inhibiting or reaction mitigating agents, whereby the olefins are caused to react with the isoparaffins in preference to the polymerization of the olefins, and whereby the tendency toward the occurrence of side reactions is reduced or eliminated and the alkylation activity of the catalyst prolonged. The invention further resides in the above process in which the products of reaction predominate in alkymers boiling within the gasoline range and are substantially free from products of polymerization.

The invention further resides in reacting the lower isoparaffinic hydrocarbons with the aforementioned olefins in the presence of an acid catalyst containing an oxidation inhibiting and reaction mitigating agent such as polyhydric alcohols, mixed polyhydric alcohol ethers, and relatively higher boiling aliphatic ethers. The invention also includes the use of relatively small proportions of the above agent or agents, quantities ranging from about 1% to 10% of the total catalyst employed being sufficient in most cases.

The invention still further includes the alkylation of isoparaffinic hydrocarbons of less than seven carbon atoms per molecule with the described olefins in the presence of a catalyst comprising a mixture of a strong acid, such as sulfuric acid of 90 to 100% H_2SO_4 content, with a suitable oxidation inhibiting and reaction mitigating agent, said catalyst promoting the combination of said olefins with the isoparaffinic hydrocarbons to produce higher boiling paraffinic hydrocarbons of a branched chain type boiling within the gasoline range, having high antiknock values and being substantially free from polymers within the gasoline boiling range.

The invention still further includes the process of reacting isoparaffinic hydrocarbons of less than seven carbon atoms per molecule with normally gaseous olefinic hydrocarbons, or olefin-containing gases substantially free from ethylene, in the presence of a catalyst consisting of sulfuric acid, benzene sulfonic acid, phenol sulfonic acid, or the like, and of relatively small proportions of polyhydric alcohols, their esters, or higher aliphatic ethers, or mixtures thereof, whereby the olefins are caused to react with the isoparaffins in preference to the polymerization of said olefins, and whereby the tendency toward the occurrence of side reactions is reduced or eliminated and the alkylation activity of the catalyst is prolonged.

Furthermore the invention in one of its embodiments also includes the realization of the above reactions substantially in the liquid phase. This can be realized by conducting the reaction at

pressures sufficient to maintain the reacting hydrocarbons in a liquid state.

The following examples are presented to show the advantages obtained when using as a catalyst a material comprising a mixture of sulfuric acid with a suitable mitigating agent, such as for example di-amyl-ether. In these experiments the isoparaffinic fractions employed comprises a narrow cut obtained from the stabilization of natural gasoline and an analysis of this fraction indicated that it consisted of approximately 89% isobutane, 3% normal butane and 8% propane. It is obvious that the isoparaffinic fraction to be alkylated according to the present invention may consist of hydrocarbons other than isobutane such as, for example, isopentane, or may comprise a mixture containing these and other isoparaffins.

The specific olefin-containing fraction employed in the experiments was derived from petroleum cracking operations and had substantially the following composition:

	<i>Percent by volume of liquid</i>
Ethylene	0.57
Ethane	4.50
Propylene	24.27
Propane	30.28
Isobutane	7.33
Isobutylene	12.63
Normal butylene	12.10
Normal butane	8.32

It is thus seen that the above olefin-containing gases contained about 49.0% unsaturates, exclusive of ethylene, the ratio of propylene to the butylenes being about 1:1.

Two runs were made in one of which sulphuric acid of 90.9% H_2SO_4 content and the other of which sulphuric acid of the same strength to which 5% of di-amyl-ether has been added were respectively employed as the catalyst. In each case the reaction was continued for eight hours at a temperature of about 75° F. and at a pressure of approximately 90 lbs. per square inch gauge.

The procedure used was as follows: About 2700 milliliters of the above described isobutane-containing fraction was first commingled with 3000 milliliters of the given catalyst, and about 2500 milliliters of the olefin-containing fraction gradually conveyed to the reaction zone, the rate of the olefin addition being about 2.0 milliliters per minute. During the reaction, the mixture was maintained in a state of violent agitation. After all of the olefinic stock had been added, agitation was discontinued, the acid phase allowed to separate, and the hydrocarbon product withdrawn and stabilized. This stabilization may be obtained by distilling the hydrocarbon phase in a reflux column under pressure to a temperature of about 60° to 65° F. and a pressure of about 15 pounds absolute. The residual fraction comprised a hydrocarbon product predominating in products of alkylation boiling within the gasoline range.

In the experiment in which 90.9% sulfuric acid alone was employed as the catalyst, the stabilized reaction product comprised 142% of the volume of the olefins present in the charging stock. Of this product approximately 88% by volume distilled over at 310° F., the resulting distillate, equivalent to about 115% by volume of the olefins originally charged, containing no products of polymerization. The 310° F. end point of the

distillate was selected because it satisfied the United States Army Air Corps Specification No. 2-95 for aviation gasoline.

On the other hand, the yield of the stabilized reaction product from the second experiment, in which the diamyl ether was added to the sulfuric acid, was 155.2% by volume of the olefins charged. Approximately 87% of this product distilled over at 310° F., the resulting distillate also free from polymers, being equivalent to 121% by volume of the olefins charged.

The above runs clearly disclose the advantages of employing as a catalyst a mixture of sulfuric acid with a suitable mitigating agent rather than sulfuric acid alone.

Thus, the sulfuric acid diamyl-ether mixture allowed the realization of approximately 6% more aviation gasoline than was obtained by the use of the sulfuric acid alone.

When the reaction is to be effected in the liquid phase, it is preferable to maintain a concentration of isoparaffins in excess of the quantity theoretically necessary to combine with the olefins. This excess should exist during the whole course of the reaction. Therefore, in the preferred embodiments of the invention the isoparaffins enumerated above, or their mixtures, are first commingled with the catalyst containing the described oxidation inhibiting and reaction mitigating agent. Thereafter, the olefins are slowly and gradually introduced into the mixture. The presence of an excess of isoparaffins, combined with the relatively slow and gradual addition of the olefins is necessary to prevent any local over-concentration of the olefins, this over-concentration favoring the undesirable polymerization of the olefins instead of the alkylation of the isoparaffins. In other words, the constant presence of an excess of isoparaffinic molecules increases the chances of contact of each activated olefin with an activated isoparaffin molecule. Simultaneously, the relatively slow addition of the olefins, together with the agitation of the mixture, tends to disperse the olefin molecules, thus decreasing their concentration and also favoring the possibility of the alkylation reaction to take place in preference to the polymerization of the olefins.

The above disclosure is presented in connection with the alkylation of isoparaffins with olefins, and emphasizes the simple addition of the relatively low molecular weight normally gaseous olefins (preferably above ethylene) to the specified isoparaffins. In addition it was discovered that in reacting the isoparaffins with normally liquid olefinic hydrocarbons the reaction product comprises a large proportion of saturated branched chain hydrocarbons boiling within the gasoline range. Such hydrocarbons evidently could be formed by an initial scission of at least one of the original reacting hydrocarbons into a plurality of molecules of lower molecular weight, and the subsequent reaction of these lower molecular weight hydrocarbons to produce the branched chain paraffinic hydrocarbons. The same result may also be due to a simple addition of the introduced olefinic molecules to the isoparaffinic molecules, followed by a scission of the product. Specifically, this alkylation reaction, therefore, may be called a "cracking alkylation" reaction in order to distinguish it from the straight or simple addition of an introduced olefin to the isoparaffin, as this has been described hereinabove.

The "cracking alkylation" reaction may thus be

described as including the step of reacting olefin molecules with isoparaffinic molecules to produce one or more paraffinic alkylmer molecules which have molecular weights of less than that which would be obtained providing the reaction were of the simple addition type in which, as previously stated, an olefinic molecule introduced into the sphere of reaction combines with an isoparaffinic molecule to produce a branched chain saturated molecule having a molecular weight equal to the sum of the molecular weights of the reacting olefin and isoparaffin. Therefore, the invention also includes the reaction between the described isoparaffins and certain of the olefins (particularly the normally liquid olefins), in the presence of the catalyst containing the oxidation inhibiting and reaction mitigating agent, to produce both the simple alkylation of the isoparaffins by the olefins added, and the cracking alkylation in which, as stated, alkymers are produced which have a lower molecular weight than would be obtained by simple addition of an olefin to an isoparaffin. The higher molecular weight olefins, for example above dodecenes, however appear to be undesirable since the products of reaction, when using these high molecular weight olefins, contain excessive percentages of polymers boiling above the gasoline range.

The term "gasoline boiling range" is used here to denote the average boiling range of fuels used in automobile engines. Generally speaking, such a gasoline has an initial boiling point of about 100° F., and a maximum or end point of around 425° F. The term "atmospheric pressure" refers to pressures in the neighborhood of 760 mm. of mercury, while "atmospheric" or "room" temperature relate to temperatures in the vicinity of 70° F. to 75° F.

In carrying out the invention the apparatus used and the conditions of operation chosen in respect to temperature, pressure and proportions

of reacting constituents, etc., may be varied to suit individual cases. Thus, although the alkylation reactions described herein were realized at substantially room temperatures, under certain conditions lower or higher temperatures may be employed. Also, the rate and manner of adding the olefin may be altered. Furthermore, other mitigating agents, such as have already been enumerated, may be used with equal facility and in proportions higher or lower than the 5% suggested in the above illustration. The process described herein may also be applied to individual olefins and/or isoparaffins produced by special chemical methods or by a suitable fractionation of mixtures in which they occur.

Many other pertinent and equally different embodiments may be made by those skilled in the art, without departing from the spirit and scope hereof, and it is therefore understood that there is no intention to be limited by the specific embodiments disclosed herein except as defined by the appended claims.

We claim:

1. A process for producing motor fuels which comprises reacting isoparaffinic hydrocarbons of less than seven carbon atoms per molecule with olefinic hydrocarbons having more than two carbon atoms per molecule in the presence of an alkylating catalyst and diethyl ether.

2. A process for forming alkylated branched chain paraffinic hydrocarbons boiling within the gasoline range and substantially free from polymers, which comprises reacting isoparaffinic hydrocarbons of less than seven carbon atoms per molecule with normally liquid olefins preferably of less than thirteen carbon atoms per molecule, in the presence of a catalyst mixture containing strong sulfuric acid and diethyl ether.
